UNITED STATES PATENT OFFICE.

JOSEPH W. MICHEL, OF BINGHAMTON, NEW YORK.

CIGAR-PACKAGE.

No. 906,444.

Specification of Letters Patent.

Patented Dec. 8, 1908.

Application filed April 7, 1908. Serial No. 425,615.

To all whom it may concern:

Be it known that I, JOSEPH W. MICHEL, a citizen of the United States, residing at Binghamton, in the county of Broome and State of New York, have invented certain new and useful Improvements in Cigar-Packages, of which the following is a specification.

My invention relates to the form of a cigar which most readily adapts itself to be compressed into a neat package or bunch for protection from the air, and a peculiar form of cover to protect from the air, the package of cigars mentioned, and to the preservation therein of the aroma and peculiar qualities of the cigar just as they are when originally placed in the package. I accomplish this by means of a peculiarly shaped cigar which readily adapts itself to be compressed into a compact and peculiarly formed bunch which will most readily take on a tobacco cover or wrapper and by means of the said cover or wrapper which is rolled about the bunch, completely conforming to the shape of the bunch and there securely sealed; said package also containing within it and on the outside of the wrapper, a combination of means whereby it may be readily opened at any time from end to end or only partly opened for the removal of a single cigar or for the removal of the entire contents without breaking up the wrapper or covering, which would result from random hand manipulation or breaking open at random of the package by the fingers.

My cigar is of such a peculiar shape and the package formed therefrom is of such a shape as to be readily covered and sealed up, so that the bunch is completely protected from the loss of moisture, aroma, strength or flavor, by evaporation.

It has been found that when a package of cigars is once covered and sealed it is difficult to open the bunch or break into it with the fingers to remove a cigar, without completely destroying the wrapper. In my device the package preserves, in a neat and compact form, all the original value and qualities while in show cases and on sale or in the hands of the consumer waiting for use, with ready means for opening the package without destroying completely, the protecting features of the wrapper.

Figure 1, represents a perspective view of my device. Fig. 2, represents a longitudinal section of the same. Fig. 3, represents a

perspective view showing a cigar in the act of being removed from the case. Fig. 4, represents a side view of one of the cigars. Fig. 5, is a cross-section taken on line 5—5 of Fig. 2. Fig. 6, is a cross-section taken on line 6—6 of Fig. 4.

Similar letters refer to similar parts throughout the several drawings.

A, B, C and D represent cigars made in the peculiar forms shown in Figs. 4 and 5.

F is the wrapper or covering of the bunch of cigars mentioned and usually wound around in such a manner, in spiral form about the bunch, as will give the greatest strength and security to the cover as it is fastened about the bunch of cigars, and it is made of several layers of tobacco.

For the purpose of my invention I select for a cover or envelop, a certain kind of tobacco, and having about it as much of an impervious element as is possible, to perfectly seal the contents against outside atmospheric influences and which will preserve and hold the full flavor of the cigars within. In my device, the wrapper for the bunch of cigars will preserve indefinitely the full flavor and quality of the cigars contained therein, and being of the same kind of material as the cigar itself, does not take up unto itself or absorb into itself from the cigars any of the peculiar qualities of the cigar, so that this wrapper has a twofold value of a preserver of the aromatic features of the cigar and as a protector of the package, as before mentioned. I first shape my cigar as shown in Fig. 4. I then gather the several cigars into a bunch in which the several cigars are held as shown in Fig. 2, and the bunch is compressed into the form shown in Fig. 3, so that the shape of the bunch assumes the form shown in Figs. 2 and 5. To one of these cigars, preferably the one on the outside of the bunch, I attach the cord G, which serves

as not only my opening device but as a removing device of the contents. I then lay the cord longitudinally upon the bunch, following the conformation of the same, and then roll about the bunch the wrapper F, so manipulating it as to be closely bound about the bunch, the cord G being of sufficient length to extend beyond the end of the package, as shown in Fig. 1. I then seal the wrapper by an adhesive substance so that it will become a hermetically sealed package. I then place on the other side of the package, either by print or indentation, a line of dots

or indentations. When I desire to open the package thus sealed to remove a cigar, holding the package in one hand I grasp the outer end of the cord G with my other hand and 5 draw longitudinally upon the cord and cause the cord to cut an opening and to follow a course along the dotted line F in tearing its way outward, large enough for the end of the cigar to extend outwardly through it, and to 10 cut its way sufficiently far, to open the cover to the other end of the package so that a cigar can be removed, as shown in Fig. 3, but for all ordinary purposes only a sufficient opening need be made to allow this end of 15 the cigar to protrude, and thus it can be removed by being pulled out longitudinally by the cord G, and thus only a small opening is made in the wrapper and by reason of the adhesive substance in the wrapper a certain 20 spring and stiffness is given to it which immediately closes the opening.

The remaining bunch B, C, D, etc., being now loosened up, it is quite easy, by a pressure of the fingers, upon the wrapper, F to 25 cause another cigar B to protrude and be taken out with the fingers when desired for use, without further opening the package, or the cord G by a lateral pull can be drawn through the wrapper until it cuts the opening 30 from end to end of the package as before mentioned, and whenever it is desired to remove the cigars. By this method the slot becomes of sufficient length to permit the 35 entry of the fingers for the removal of the cigars, the opening again closing after each removal.

Having thus described my invention what I claim as new and for which I desire Letters Patent is as follows:

40 1. The combination with a bunch of cigars or cheroots, of a sealed covering generally conforming to the shape of the bunch of cigars contained therein, with an opening and removing device attached to a member of the 45 contents to facilitate the opening of said covering and the removal of said cigars when required, substantially as and for the purposes therein set forth.

2. In combination with a bunch of cigars or cheroots, a protective covering of tobacco shaped to cover the bunch within and securely sealed at both ends, hermetically sealing the contents therein; an opening device, the interior end fastened to one member of the bunch with the other end projecting through and extending outside of the sealed end of the wrapper, substantially as and for the purposes therein set forth. 50 55

3. The combination with a bunch of cigars, of a wrapper of suitable flexible material securely wound around the bunch and sealed on the sides and at the ends, hermetically sealing the contents and a stripping and severing or removing device, one end of which extends within one end of the wrapper and 60 the upper surface of the bunch, the interior end being fastened to a cigar within, substantially as and for the purposes therein set forth. 65

4. A bunch of cigars, each cigar composing said bunch having three side surfaces and curved ends, a wrapper about said bunch composed of any flexible material forming an impervious covering; said bunch having also an opening device extending within the package and there fastened to one or more of the members of the interior bunch, the other end projecting outside the wrapper; a series of marks on the outside of the wrapper forming a guiding line to guide the direction of the 75 movements of the opening or removing device, when in operation to open the package, and also to indicate the location of the opening device within the interior of the package, all substantially as and for the purposes 80 85 therein set forth.

5. A cigar package comprising a series of closely bunched cigars, a close fitting cover to the same, and a cord attached to one of said cigars and serving to sever the cover. 90

In testimony whereof I have affixed my signature in the presence of two witnesses.

JOSEPH W. MICHEL.
